(57) **CLAIM**

I claim the ornamental design for an expandible collapsible fishing lure, as shown and described.

DESCRIPTION

FIG. 1 is a perspective view of the expandible collapsible fishing lure;

FIG. 2 is a right side elevation view of the expandible collapsible fishing lure;

FIG. 3 is a left side elevation view of the expandible collapsible fishing lure;

FIG. 4 is a top plan view of the expandible collapsible fishing lure;

FIG. 5 is a bottom view of the expandible collapsible fishing lure;

FIG. 6 is a front elevation view of the expandible collapsible fishing lure; and,

FIG. 7 is a rear elevation view of the expandible collapsible fishing lure.

The depiction of the fishing hooks and segment boundary lines shown in dashed lines on the expandible collapsible fishing lure, are shown for environmental purposes, and form no part of the claimed design.
